UNITED STATES PATENT OFFICE

EDWARD B. GROSS, OF BUFFALO, NEW YORK

SPACE GUARD FOR DRY CLEANING MACHINES OR THE LIKE

Application filed July 5, 1927. Serial No. 203,291.

This invention relates to improvements in space guards for dry cleaning machines or the like of the type having a stationary outer casing and a rotatable or oscillatory inner cylinder and which uses an inflammable cleaning substance.

In such machines means are usually provided for preventing articles from falling into the space between the casing and cylinder. Machines of this type also are generally equipped with fire extinguishing mechanism which, upon the occurrence of a fire, is operative automatically to close the doors of the casing and cylinder and to release a fire extinguishing agent. Unless the door of the casing be fully closed, air will enter the machine with the result of preventing or at least delaying the extinguishment of the fire while at the same time flames from the interior of the casing may escape with the liability of burning the operatives or of starting a fire in the building. In machines as heretofore manufactured, when the space guard is in operative position the door of the casing cannot be fully closed and the fire hazard of such machines is correspondingly greater for the reasons pointed out.

The objects of the invention are to overcome the fire hazard objections of prior machines and to provide an exceedingly simple and easily manipulated space guard which in operative position interposes no obstacle to the complete closure of the door of the casing under fire emergency conditions. With these objects in view I provide, for the purpose of closing the space between the casing and cylinder, a combination which consists of an apron, functioning as a closure, and having slidable and pivotal components of movement and supporting elements for said apron which are wholly enclosed in said space and by which the movements of the apron, in changing it from one position to another, are prescribed. The invention consists generally in such features of combina-

tion and structural details appurtenant thereto.

An embodiment of my invention is illustrated in the accompanying drawings, wherein:

Fig. 1 is a vertical transverse section of the machine. 50

Fig. 2 is a section on the line 2—2 of Fig. 1.

Fig. 3 is a detail sectional view showing the guard plate or apron in open position. 55

Fig. 4 is a detail sectional view at an angle to the plane in which Fig. 3 is taken, the guard plate or apron being shown in open position.

Fig. 5 is a fragmentary detail perspective view of the guard plate or apron in operative position. 60

Fig. 6 is a perspective view of the guard plate or apron. 65

Fig. 7 is a perspective view of one of the supporting members for the guard plate or apron, the other being similarly constructed.

The machine includes an outer casing 10 of substantially cylindrical form and having a hinged door 11 to facilitate the transfer of articles to or from an inner rotatable cylinder 12 which is mounted on a shaft 13 and driven by any suitable gearing (not shown). The cylinder has a door, similar to the casing door which, when the machine is in operation, may be held closed by any suitable means. When articles are to be transferred to or from this cylinder, the outer door is opened to a substantially upright position where continued motion is prevented by the fire control mechanism (not shown) which is attached to the bracket indicated at 10—a and where the door's center of gravity prevents it from falling back to closed position. The inner door is opened to a similar position where it leans against the outer door. The fire control mechanism which is generally provided, includes means mounted on the casing to kick the outer door to closed position upon the occurrence of a fire. It is ap- 80 75 85 90

parent, of course, that the outer door, when so actuated to closed position, will actuate the inner door to its closed position.

The above specified construction is that of a dry cleaning machine of the usual type and to which this invention is applicable.

As stated above, this invention relates particularly to the space guard or apron and its supporting members. The latter comprises a flat vertical wall 15 provided on its inner side with a marginal flange 16 of general U-shape which functions as a guide and support. The marginal flange has a recess 17 at its upper end and a projection adjacent said recess providing an overhanging shoulder 18 and it is further provided with a projection 19 extending horizontally outward from a point near its upper end to support the apron 20. The apron 20 is in the form of a flat plate having along its lower or inner edge, a reinforcing bar 21 provided with end trunnions 22, these, in the open position of the apron, resting upon the bottom of the guides provided by the marginal flanges 16, the upper corners of the apron at the same time lying within the recess 17. The apron is also provided with handles 23 whereby it may be manipulated. The sides of the apron, adjacent the trunnions, are cut away at 24 for clearance purposes as explained herein-after.

Assuming that the machine has just been brought to rest after the cleaning operation has been completed and the apron is in open position (Fig. 3), the operation is as follows:

The door 11 is opened to its upright position and the door 14 unlatched and opened to a similar position. Before the articles are to be removed, the space between the casing and cylinder should be covered or closed. This is done by raising the apron vertically by the handles 23 until the end trunnions 22 strike the shoulders 18. In this position it is noted that the cut away portions 24 of the apron extend beyond the shoulders 18 permitting the sides of the apron to clear said shoulders when the apron is rotated about its trunnions toward the cylinder. After the apron has been rotated to a substantially horizontal position, the sides of the apron will rest on the projections 19 and the free edge portion of the apron will rest on the lower wall of the opening which is normally closed by the door 14 whereby the space between the casing and cylinder is completely covered. The articles may now be removed and in such removal if any of them drop as they are taken from the cylinder, they will fall upon the apron 20. After refilling the cylinder with other articles to be cleaned, the apron is rotated back to its vertical position and dropped into the supporting members whereupon the doors are closed and the machine started.

From this it follows that when any articles are being transferred to or from the machine, the apron is in closed position. If, at this time, the cleaning substance should become ignited, the fire control mechanism will be actuated to close both doors. The complete closure of the inner door is prevented by the apron, but sufficient clearance remains between the inner and outer doors to allow the complete closure of the outer door. With the outer door thus fully closed, the fire is confined to the interior of the machine and admission of air thereto is effectually prevented whereby the fire can be readily smothered. It is obvious that regardless of the position of the apron, it can never interfere with the closure of the outer door.

Having fully described my invention, I claim:

1. In a dry cleaning machine, an outer casing and an enclosed cylinder, each provided with doors, in combination with an apron, supporting members for said apron having guideways formed therein in which said apron is slidably and pivotally mounted, said supporting members being mounted within said casing adjacent the casing door and formed to support said apron in either of two positions; in one of which it extends vertically without obstructing the space between the casing and cylinder and in the other of which it extends substantially horizontally across said space with its free edge overlying and resting upon the lower wall of the door opening of the cylinder.

2. In a dry cleaning machine, an outer casing and an enclosed cylinder, each provided with doors, in combination with an apron, supporting members for said apron having vertically arranged U-shaped elements mounted within said casing and each formed with a recess at its upper end and an overhanging shoulder adjacent said recess, the apron having end parts which normally rest upon the lower portions of said elements and are slidable therein and which when the apron is raised engage said shoulders as stops and provide trunnions about which the apron may be swung to a position in which it extends across the space between said cylinder and casing.

3. In a dry cleaning machine, an outer casing and an enclosed cylinder, each provided with doors, in combination with an apron, supporting members for said apron having vertically arranged U-shaped elements mounted within said casing and each formed with a recess at its upper end, an overhanging shoulder adjacent said recess and a projection near its upper end, the apron having end parts which normally rest upon the lower portions of said elements and support the apron in a vertical position in which it is slidable in a vertical plane prescribed by the form of said elements, the

apron also having recesses adjacent said end parts whereby when the apron is fully raised the end parts engage said shoulders as stops and provide trunnions about which the apron may be swung to a position in which it extends across the space between said cylinder and casing and in which it engages said projections as supports, said recesses permitting such swinging movement.

6 10 In testimony whereof I affix my signature.
EDWARD B. GROSS.
